UNITED STATES PATENT OFFICE.

GEORGE R. MCLEAN, OF HINSDALE, ILLINOIS.

BUNDLE CARRIER.

Application filed October 16, 1924. Serial No. 743,885.

To all whom it may concern:

Be it known that I, GEORGE R. MCLEAN, a citizen of the United States, residing at Hinsdale, in the county of Du Page and 5 State of Illinois, have invented certain new and useful Improvements in Bundle Carriers, of which the following is a specification.

This invention relates to a bundle carrier 10 so designed that it will serve for the transport of goods or articles of many sorts and sizes. In short, it is so designed that it will readily serve for the carrying of objects of such diverse character as fire wood and vegetables 15 or the like, making it an article of general utility in the household.

It is further so designed as to dispense with any form of rigid frame work either of wood or metal, so that it may readily be 20 laundered as occasion may require, or may be rolled up and packed into a very small compass when not in use.

Further objects and characteristics will appear from a detailed description of the invention which consists in the features of construction and combinations of parts hereinafter described and claimed.

In the drawings:

Figure 1 is a plan view of the carrier in 30 open or extended condition with a plurality of fire logs laid within it;

Fig. 2 is a side elevation with the flaps lifted up in position for carrying; and

Fig. 3 is a view showing the carrier partly 35 open for the reception of apples, vegetables or like small articles.

The carrier is formed of canvas or other strong and durable fabric and comprises a body portion A formed from a blank of 40 rectangular shape having the corner sections B turned in and secured to the body section by lines of stitching C. The corner sections along the folding line, embrace the ends of a strip D which protrudes from the space 45 between the overlaps or folds to afford a loop E which constitutes a handle grip. Across the center of the body on the inside is extended a pocket flap F, the ends of which are stitched under the lapped over binding 50 edges G of the body section. The pocket flap is otherwise unattached, being free along its side edges to permit it to be lifted away from the body for the packing of objects or 55 articles beneath it, as indicated in Fig. 3.

When the carrier is used for the transport of large or bulky objects like sticks of fire

wood, the same are laid outside of the pocket flap, as in Fig. 1, in which case the flap affords a reinforced base or bottom for the carrier, but when it is desired to transport 60 small objects or articles like fruit or vegetables which require more or less protection against displacement, the same are packed in under the flap, as in Fig. 3, after which the end sections of the carrier are folded 65 upwardly which will bring them into contact with the edges of the pocket flap on each side so as to afford a full and complete enclosure for the articles thus packed and housed, so that the same may be readily transported 70 without permitting displacement.

In cases where a large number of articles, such, as, for instance, a quantity of apples or potatoes are being thus transported, the 75 packing of the articles under the flap will lift or bulge the same upwardly thereby drawing in slightly on the ends of the pocket flap which has a tendency to bend up the side edges of the body section, so that the carrier as a whole tends to assume the bottom formation of a shallow basket, and this 80 tendency further prevents the contents of the carrier from falling or rolling out.

The device is so formed that it permits the 85 articles to be readily positioned within the carrier and transported and discharged without the slightest difficulty, since the mere act of lifting up the ends of the carrier by the handle grips will serve to bring the several parts into enclosing relation to one another, and the mere act of releasing the 90 handle grips will cause the carrier to open up in position to permit discharge of its contents.

The carrier will be found particularly 95 serviceable in marketing in that the user is enabled to open and spread the carrier flat on a market or grocery table and load into it a miscellaneous assortment of groceries or the like, and thereafter readily carry the same to a car and conveniently and quickly 100 lift and store the same within the car in relatively small compass and without danger of scratching or marring the car as often happens where boxes are used for a like purpose.

I claim:

1. A bundle carrier comprising a body of flexible material provided at each end with a handle grip and provided across its center on the inside with a pocket flap secured at 110 each end to the body and so arranged as to

present its unsecured edges for contact with the proximate portions of the body when the ends of the body are flexed upwardly to bring the handle grips into close relation to one another, substantially as described.

2. A bundle carrier comprising a body of flexible material of elongated formation and having its corners folded inwardly and secured to the face of the body, a handle grip secured to each end of the body at the center and a pocket flap extending across the middle of the body on the inner side thereof and

secured at its ends to the side edges of the body, the side edges of the pocket flap being unsecured to the body and adapted to be 15 lifted therefrom to permit the packing of articles between the body and the pocket flap, the arrangement being such as to afford contact between the unsecured edges of the pocket flap and the proximate portion of the 20 body when the ends of the body are lifted to bring the handle grips into close relation to one another, substantially as described.

GEORGE. R. McLERAN.
